* cited by examiner

Primary Examiner — Holly Baynham*Assistant Examiner* — Rhea Shields(74) *Attorney, Agent, or Firm* — Henry M. Feiereisen LLC;
Ursula B. Day(57) **CLAIM**

The ornamental design for a container of hygiene caps, as shown and described.

DESCRIPTION

FIG. 1 is a top plan view showing my new design;
 FIG. 2 is a front elevational view showing my new design;
 FIG. 3 is a left side elevational view thereof;
 FIG. 4 is a rear elevational view thereof;
 FIG. 5 is a right side elevational view thereof;
 FIG. 6 is a bottom plan view thereof; and,
 FIG. 7 is a top, front and side perspective view of thereof.
 In the drawings, the broken lines are for the purposes of illustrating environment only and form no part of the claimed design.
